LOCK FOR OUTBOARD MOTORS

John Leslie Douglas, Minneapolis, Minn., assignor
to C. F. Noltmier, Minneapolis, Minn.

Application April 22, 1938, Serial No. 203,567

10 Claims. (Cl. 70—19)

My invention relates to locking devices and particularly to locking devices for clamp screws.

Outboard motors for boats are portable in nature and relatively valuable and, since they are 5 removably attached to boats by means of clamps, many thefts of such motors from boats and motor storage racks occur.

A general object of my invention is to provide locking means readily associatable with a mounting bracket of any outboard motor for locking the bracket against removal from a boat or rack.

A more specific object is to provide such a locking device which may be readily substituted 15 for the original clamping screw of any outboard motor mounting bracket.

Another object is to provide such a device comprising a clamping screw and a body screw-threadedly mounted thereon, releasably fixable 20 thereon, and arranged for abutment with the clamp yoke to restrain the clamping screw from loosening movement thereof.

A further object is to provide such a locking device of effective, light, compact, simple, rugged 25 and inexpensive construction.

These and other objects and advantages will more fully appear from the following description made in connection with the accompanying drawing wherein like reference characters refer 30 to the same or similar parts throughout the views, and in which:

Fig. 1 is a partially broken away side view of my locking device shown in operative association with the mounting bracket of an outboard 35 motor;

Fig. 2 is a sectional view taken along the line 2—2 of Fig. 1 as indicated by the arrows;

Fig. 3 is a sectional view taken along the line 3—3 of Fig. 1 as indicated by the arrows;

Fig. 4 is a view similar to Fig. 3 but of another 40 form of my device; and

Fig. 5 is a sectional view taken along the line 5—5 of Fig. 4 as indicated by the arrows.

Referring to the drawing my outboard locking device is shown operatively associated with an outboard attachment bracket A and a member B which may be the rear end board of a boat or a part of a storage rack for outboard motors. The bracket A includes a backing portion 6, yoke 7, and the bossed apertured portion 8 to which a motor may be swingably attached in the usual manner. The yoke 7 includes an apertured internally screw-threaded free end portion 9 for receiving a clamping screw in screw-threaded engagement therewith.

The clamping screw of my device is constructed along the general lines of construction of clamping screws for outboard motor brackets. The clamping screw 10 is provided with screw-threads 10a and a T-handle portion 10b in the usual manner. Longitudinally extending recesses or grooves 10c are provided in the screw-threaded portion of the screw 10. The end of the screw 10 which engages the object to be clamped is provided with an object engaging 10 element 11 rotatably attached to the screw 10. The element 11 has a centrally apertured hub portion 11a through which a pivot screw 12 extends. The pivot screw 12 has a head 12a formed similarly to the head of a flat headed 15 machine screw. The opposite end 12b of the screw 12 is of reduced diameter and is provided with screw-threads by means of which the screw 12 is screw-threadedly engaged in a screw threaded aperture 10d formed in the end of the 20 screw 10. The element 11 has thereon a narrow annular flange 11b for engaging an object such as the member B. A pointed pin 13 is mounted in the head 12a of the screw 12 in such a manner that the pointed end of the pin 13 will be 25 forced into an object upon which the bracket A is clamped.

I provide a body 14 which is apertured and internally screw-threaded for screw-threaded mounting thereof on the screw-threaded portion of the screw 10. The body 14 includes a portion 14a situated eccentrically of the screw-threaded portion of the body 14 and comprising a casing of a cylindrical lock operable by a key 15 and including a lockable plug 16 which is 30 rotated in response to rotation of the key 15. The plug 16 carries thereon a pin 16a disposed eccentrically thereof. The body 14 and the portion 14a thereon contains a bolt 17 in a suitably bored part of the body 14 and portion 14a. The 40 bolt 17 is slidable radially of the screw 10 toward and away therefrom and at its inner end is adapted to be received in any of the grooves 10c. A helical compression spring 18 is disposed between the outer end of the bolt 17 and a plug 45 19 screw threadedly mounted in the portion 14a of the body 14 as shown. The eccentrically located spring 18 extends through a suitable transversely extending slot in the outer portion of the bolt 17 so that the bolt 17 will be projected 50 and retracted responsive to rotation of the plug 16 by means of the key 15. From the above it should be apparent that the body 14 is normally rotatable relative to the clamping screw 10, but may be fixed thereon against rotation by means 55

of the bolt 17 and one or the other of the grooves 10c in as many positions relative to the screw 10 as the number of grooves 10c.

Means is provided whereby the body 14 is limited in regard to rotation thereof relative to the yoke 7. For this purpose I provide an abutment finger 20 projecting from the portion 14a of the body 14 toward the yoke 7 so that the path of the abutment element 20 when the body 14 is rotated relative to the yoke 7 will intersect a portion of the yoke 7 whereby the element 20 will abut the yoke 7 to limit rotation of the body 14 relative to the yoke 7.

To replace an ordinary clamping screw used in the mounting bracket of an outboard motor with my device the ordinary clamping screw is first removed; next the body 14 is placed relative to the yoke 7 of the mounting bracket, as shown in Fig. 1; the clamping screw 10 with the element 11 removed therefrom is then screwed into the body 14 and the screw threaded portion 9 of the yoke 7. The element 11 may then be attached to the free end of the screw 10 by means of the screw 12a. In use of the device the clamping screw 15 may be used in the usual manner to clamp the bracket A onto a member such as the member B. When the clamping screw has been tightened the body 14 is preferably swung in a counter-clockwise direction to bring the abutment finger 20 into engagement with the yoke 7, as shown in the drawing. When this has been done the screw 10 may be further tightened until one of the grooves 10c is aligned with the bolt 17 whereafter the key 15 may be turned to project the bolt 17 into the groove 10c aligned therewith. The key 15 may then, of course, be removed. Obviously the device when locked as described above will prevent loosening or unscrewing rotary motion of the clamping screw 10 relative to the yoke 7.

Figs. 4 and 5 illustrate a slightly different form of my device. In this form the device is constructed in the same manner as the device shown in Figs. 1 to 3 inclusive with the exception that the abutment finger 20 is replaced by a cylindrical element 21 carried by the portion 14a of the body 14. The yoke 7 is provided with an aperture 22 drilled or otherwise formed therein to receive the cylindrical element 21.

It should be apparent that I have invented a simple, compact, rugged, and inexpensive locking device for outboard motors, and that the device is readily adapted for installation in operative association with the mounting bracket of any outboard motor. It is also apparent that my device is readily adapted for use in connection with clamping screws other than those found in outboard motor brackets.

It will, of course, be understood that various changes may be made in the form, proportions, details, and arrangement of the various parts without departing from the scope of my invention.

What is claimed is:

1. In combination with a screw and an internally screw-threaded apertured member wherein said screw is screw-threadedly engaged, releasable means for limiting unscrewing movement of said screw relative to said member comprising, a body with which said screw is associated in normally rotatable relation, and releasable means for so interconnecting said screw and said body as to limit relative rotation therebetween, said body being so associated with said

member that relative rotation therebetween is limited.

2. In combination with a screw and an internally screw-threaded apertured member wherein said screw is screw-threadedly engaged, releasable means for limiting unscrewing movement of said screw relative to said member comprising, a body mounted on said screw in normally rotatable relation therewith, releasable means associated with said body and said screw for fixing said body on said screw, and a portion of said body being engageable with said member to limit rotation of said body relative to said member.

3. In combination with a clamp including a yoke and a clamping screw screw-threadedly engaged in an apertured and internally screw-threaded portion of said yoke, locking means for limiting unscrewing movement of said screw relative to said yoke comprising, a body mounted on said screw in a manner normally enabling rotation of said screw relative to said body, releasable means associated with said body and said screw for restraining said screw from rotation relative to said body, and means carried by said body for abutment with said yoke to stop rotation of said body relative to said yoke.

4. In combination with a clamp including a yoke and a clamping screw screw-threadedly engaged in an apertured and internally screw-threaded portion of said yoke, locking means for limiting unscrewing movement of said screw relative to said yoke comprising, a body mounted on said screw in normally rotatable relation therewith, releasable means for fixing said body on said screw, and an element formed on said body and projecting therefrom in such manner that the path of said element, when said body is rotated relative to said yoke intersects a portion of said yoke whereby said element will abut said yoke to limit rotation of said body relative to said yoke.

5. In combination with a clamp bracket having a portion thereof apertured and internally screw-threaded to receive a clamping screw, a clamping screw screw-threadedly carried by said portion and locking means for limiting unscrewing movement of said screw relative to said bracket comprising, a body mounted on said screw in normally rotatable relation thereto, a locking element carried in said body for movement toward and away from said screw, said screw having a recess therein for receiving a portion of said element to restrain said screw from rotation relative to said body, and means carried by said body for engaging said bracket to limit rotation of said body relative to said bracket.

6. In combination with a clamp bracket having a portion thereof apertured and internally screw-threaded to receive a clamping screw, a clamping screw screw-threadedly carried by said portion and locking means for limiting unscrewing movement of said screw relative to said bracket comprising, a body mounted on said screw in normally rotatable relation therewith, a locking element carried in said body in slidable relation thereto radially of said screw, said screw having a recess therein for receiving a portion of said element to restrain said screw from rotation relative to said body, and means carried by said body for engaging said bracket to limit rotation of said body relative to said bracket.

7. The combination defined in claim 6 and said screw having additional recesses therein circumferentially displaced from said first-mentioned recess whereby said screw may be locked against

rotation relative to said body in various rotated positions relative to said body.

8. In combination with a clamp bracket having a portion thereof apertured and internally screw-threaded to receive a clamping screw, a clamping screw screw-threadedly carried by said portion and locking means for limiting unscrewing movement of said screw relative to said bracket comprising, a body mounted on said screw in normally rotatable relation therewith but in such manner as to prevent rectilinear movement of said body longitudinally of said screw, a locking element carried in said body for movement inwardly and outwardly of said screw, said screw having a groove therein extending longitudinally thereof for receiving a portion of said element to restrain said screw from rotation relative to said body, and means carried by said body for engaging said bracket to limit rotation of said body relative thereto.

9. In combination with a clamp bracket having a portion thereof apertured and internally screw-threaded to receive a clamping screw, a clamping screw screw-threadedly carried by said portion and locking means for limiting unscrewing movement of said screw relative to said bracket comprising, a body screw-threadedly mounted on said screw, a key-operated lock mounted in said body and including a bolt respectively projectible and retractible radially inwardly and outwardly of said screw, said screw having therein a series of longitudinally extending grooves each adapted for receiving a portion of said bolt to fix said body on said screw, and a rigid element provided on said body and projecting therefrom toward said yoke for engagement therewith to limit rotation of said body relative to said yoke.

retractible radially inwardly and outwardly of said screw, said screw having formed therein a groove extending longitudinally thereof for receiving said bolt when the same is in projected position to restrain said body from rotation relative to said screw, and an element formed on said body to project therefrom on the side thereof toward said bracket whereby said element may be placed in such position that it will engage said bracket to limit rotational movement of said body relative thereof.

10. In combination with a clamp including a yoke and a clamping screw screw-threadedly engaged in an apertured and internally screw-threaded portion of said yoke, locking means for limiting unscrewing movement of said screw relative to said yoke comprising, a body screw-threadedly mounted on said screw, a key-operated lock mounted in said body and including a bolt respectively projectible and retractible radially inwardly and outwardly of said screw, said screw having therein a series of longitudinally extending grooves each adapted for receiving a portion of said bolt to fix said body on said screw, and a rigid element provided on said body and projecting therefrom toward said yoke for engagement therewith to limit rotation of said body relative to said yoke.

JOHN LESLIE DOUGLAS.
